[57] ABSTRACT

A phase correcting network is provided to reduce the non-linearity of the phase/frequency characteristic of a delay line. The invention is applicable to delay lines which form part of a commuting hybrid. The phase correcting network includes a 3dB coupler which is terminated in a pair of susceptance loaded waveguide stubs.

**MICROWAVE PHASE CORRECTING NETWORK
UTILIZING WAVEGUIDE COUPLER HAVING
MISMATCHED PORTS CAUSED BY LATERALLY
DISPLACED END SECTION**

This invention relates to a phase correcting network and has particular application in providing improved channel centre frequency distribution in commutating hybrid multiplexers at millimetric wave-lengths.

FIG. 1 of the accompanying drawings shows a known form of commutating hybrid 10 formed of two 3dB couplers each having two inputs and two outputs. The first 3dB coupler 12 has one input connected to a load and the other input connected to receive a signal consisting of two frequencies f_1 and f_2 . A first output of the 3dB coupler 12 is directly connected to one input of the second 3dB coupler 14, the other output of the 3dB coupler 12 being connected to the other input of the 3dB coupler 14 by means of a length of waveguide 16 constituting a delay line. The action of the commutating hybrid is to separate the components f_1 and f_2 of the input signal to the first 3dB coupler 12 and these appear as separate signals on the respective outputs of the second 3dB coupler 14.

As is well known in the art, the commutating hybrid relies on the fact that the phase delay of the two frequencies f_1 and f_2 will differ after passing through the delay line 16 and if the phase difference is an odd multiple of π for one frequency and an even multiple of π for the other frequency the two frequencies would be separated.

It is also known, (see for example our copending application Ser. No. 157,308, now U.S. Pat. No. 3,727,152) to connect a plurality of such commutating hybrids sequentially in the manner shown in FIG. 2 of the accompanying drawings so as to provide a multiplexer. The chain shown in FIG. 2 operates in what is believed to be a self-evident manner to separate 16 channels arriving at the input of the commutating hybrid 10a. Of course, the operation of the arrangement in FIG. 2 is reversible and it is possible to feed in sixteen inputs over the respective channels CH1 to CH16 by feeding directly into the hybrids 10h to 10p and to obtain a single output consisting of the combination of these sixteen channels on the single waveguide connected to the commutating hybrid 10a.

FIG. 3 of the accompanying drawings shows the phase delay at the output of the delay line 16 as a function of frequency. Unlike a coaxial transmission line, a waveguide does not produce linear phase delay but instead follows the curve C in FIG. 3 which intersects the frequency axis at the point f_C corresponding to the cut-off frequency of the waveguide. Because of the non-linearity of the curve C it will be appreciated that the frequencies of the channels CH1 to CH16 cannot follow an arithmetic progression but instead must follow the curve C. If a linear progression is desired, a phase characteristic corresponding to the line 1, shown in dotted line in FIG. 3, must be followed. It is believed that it may be necessary to modify the phase delay characteristic of the delay line in the commutating hybrids with a view to obtaining this linear relationship in order to allow standardization of the frequencies used in different countries and it is an object of the present invention to provide a phase correcting network which may be used in a delay line of a commutating hybrid in a

multiplexer to improve the centre frequency distribution of the multiplexer.

In accordance with the present invention, a phase correcting network for improving the phase/frequency characteristic of a delay line includes a 3dB coupler adapted to be inserted in the said delay line and terminated in a pair of susceptance loaded waveguide stubs.

Conveniently, the susceptance loading of the waveguide stubs may be effected by providing one or more mismatches along the length of the stubs, the mismatches being achieved by laterally displacing sections of the waveguide relative to one another in the direction of the H-plane.

Each phase correcting network may correct for non-linearity within a predetermined range of frequencies and if it is desired to provide linearity over a wide range more than one phase correcting network may be connected in series with one another. It will also be appreciated from the description that follows that phase correcting circuits in accordance with the invention can be used not only to provide linearity but generally to modify the phase/frequency characteristics of a waveguide so as to follow a desired configuration within a predetermined range of frequencies.

The invention will now be described further, by way of example, with reference to FIGS. 4, 5 and 6 of the accompanying drawings.

FIG. 1 shows a known form of commutating hybrid; FIG. 2 shows the known connection of a plurality of such commutating hybrids to form a multiplexer;

FIG. 3 shows the phase delay at the output of the delay line as a function of frequency;

FIG. 4 is a block diagram of a modified commutating hybrid incorporating a phase correction circuit in accordance with the invention,

FIG. 5 is a graph generally similar to FIG. 3 showing variations in the phase characteristic of a delay line with variation of the mismatch in the stubs of the frequency correcting network, and

FIG. 6 is an exploded view of the phase correcting network shown in FIG. 4.

Referring now to FIG. 4, a modified commutating hybrid generally designated 10' includes two 3dB couplers 12 and 14 the interconnections between which include a delay line 16. To compensate for the non-linearity of the phase characteristic in the delay line 16 there is inserted in the latter line a phase correcting network which is enclosed within the dotted line and is generally designated 15. The phase correcting network 15 includes a 3dB coupler 18 whose inputs are connected into the delay line 16 and whose outputs are connected to stubs 20 and 22 which are lengths of waveguide terminated in a short-circuit represented by the symbols S/C in the drawing. Along the length of each waveguide there is a mismatch 24/26 and whilst only one mismatch is shown in each stub it is to be understood that more than one may be included if desired.

In order to explain the operation of the phase correcting network 15 in FIG. 4 let it first be assumed that the mismatches 24 and 26 are absent. At the short-circuited end of the stubs 20 and 22 the electromagnetic wave travelling in the waveguide would be reflected and the effect of this would be that any signal arriving at the 3dB coupler 18 from the 3dB coupler 12 will be passed by the 3dB coupler 18 to the 3dB coupler 14 after a phase delay corresponding to twice the

length of the stub 20. In effect, the wave arriving at one input of the 3dB coupler is split equally between the stubs 20 and 22 and upon deflection from the short-circuited ends of the stubs 20 and 22 the waves combine again to provide constructive interference at the other input of the 3dB coupler 18. If now the effect of the mismatches is considered, it will be realized that standing waves are set up within the stubs 20 and 22 and the effect of each mismatch will depend upon the intensity of the electric and magnetic waves at that point and this will in turn depend on the frequency. Thus, for certain frequencies where the electric and magnetic fields are a minimum at the location of the mismatch the mismatch will be of little effect whereas where the electric and magnetic fields are a maximum there will be partial reflection at the mismatch and this will shorten the phase delay of the signals received after reflection. The effect of various mismatches is shown in FIG. 5, in which the basic curve C has been modified to the curves C' and C'' by including mismatches of different susceptance within the stubs 20 and 22. It will be seen that where the mismatch has positive susceptance $+jB$ the modified phase characteristic is more curved than the curve C but in the same sense whereas if the susceptance is negative the curvature is in the opposite sense. It will be appreciated that by suitably choosing a negative susceptance it is possible to approach the ideal linear dotted line I within the range f1 and f2 in FIG. 5.

The physical construction of the phase correcting network will now be described with reference to FIG. 6. Two grooves 30 and 32 are machined in copper blocks 34 and 36 which upon mating together define two rectangular waveguides. The blocks 34 and 36 are provided with holes 38 through which bolts are passed to keep the blocks together. Slots 40 are formed in the dividing wall 42 between the grooves 30 and 32 and this provides for energy transfer between the waveguides and, as is known, such an arrangement can constitute a 3dB coupler. The ends of the waveguides 30 and 32 to the right of the slots in the drawing constitute the inputs to the 3dB coupler and the other ends of these waveguides constitute the outputs. Secured to the end of the blocks 34 and 36 is a further block 44 which is formed with blind rectangular bores 46 having the same dimensions as the waveguides. Elongate slots 48 are formed in the block 44 and bolts pass through these slots into the blocks 34 and 36 to secure the block 44 in position. The stubs are thus constituted by the short-circuited waveguides which terminate in the block 44 and the mismatch may be achieved by laterally moving the block 44 in an up and down direction as viewed relative to the blocks 34 and 36 so as to provide a mismatch between the sections of the stubs inside and outside the block 44.

I claim:

1. A phase correcting network for improving the phase/frequency characteristic of a delay line including a 3dB coupler adapted to be inserted in the said delay line and terminated in a pair of short circuited waveguide stubs, each of said waveguide stubs being susceptance loaded by means of at least one mismatch achieved by laterally displacing sections of the waveguide relative to one another in the direction of the H-plane.

2. A phase correcting arrangement comprising a plurality of phase correcting networks as claimed in claim 1 connected in series with one another.

5 3. A phase correcting network for improving the phase/frequency characteristic of a delay line comprising in combination

a 3dB coupler having two input ports and two output ports, said two input ports being connected into the delay line for the purpose of transporting signals to and from said delay line; and

10 first and second waveguide means, each connected to one of said two output ports and each terminating in a common short circuit so that any signal arriving at one input port of said 3dB coupler is split equally between said two waveguide means and, upon deflection from the short circuit terminations of said waveguide means, the split signals recombine in said 3dB coupler so as to provide constructive interference at the second input port of said 3dB coupler, said waveguide means imposing on said recombined signal a phase delay which, without further modification to said waveguide means, is non-linear in relationship to the frequency;

15 wherein said first and second waveguide means are adapted to be subjected to at least one mismatch caused by the lateral displacement in each waveguide means of one section of said waveguide means with respect to the other section of said waveguide means in the direction of the plane of the magnetic field of the signal, said mismatches having susceptances of such polarity and magnitude as to cause the phase-frequency characteristic of the delay line to become linear in nature.

20 35 4. A phase correcting arrangement comprising a plurality of phase correcting networks as claimed in claim 3 connected in series with one another.

40 5. A phase correcting network as recited in claim 3 wherein said first and second waveguide means are rectangular in cross section and are formed by the mating of two copper blocks, into each of which there is machined a rectangular groove.

45 6. A phase correcting network as recited in claim 5 wherein the short circuiting termination of said waveguide means comprises a further copper block containing rectangular bores, one for each waveguide means and of the same dimension as said waveguide means, and so positioned at the opposite end of said waveguide means from said 3dB coupler that said waveguide means may be subjected to lateral mismatch by moving said further copper block in a direction perpendicular to said waveguide means.

55 7. In a commutating hybrid network which includes a first 3dB coupler having two input ports, one connected to a load and the other connected to receive a multifrequency signal, and two output ports; a second 3dB coupler having two input ports, a first input port connected directly to the first output port of said first coupler and a second input port connected indirectly to the second output port of said first coupler, and two output ports for transmitting two output signals;

60 65 and a delay line means in the connection between the second output port of said first coupler and the second input port of said second coupler to form the indirect connection therebetween so that a multifrequency signal transmitted by the second output port of said first coupler and passing through said

delay line means undergoes separation into component signals so as to introduce a phase delay between said component signals, with the relationship between the phase delay and the frequency being non-linear in nature;

5

the improvement wherein said delay line means comprises a phase correcting network which includes a third 3dB coupler having two input ports, a first input port connected to the second output of said first coupler, and a second input port connected to the second input port of said second coupler, and two output ports; and

10

first and second waveguide means, each connected to one of the output ports of said third 3dB coupler and terminated in a short circuit, and each adapted to be subjected to at least one mismatch caused by the lateral displacement in each waveguide means of at least one section of said waveguide means with respect to the other section of said waveguide means in the direction of the plane of the magnetic field of the signal, said mismatches having susceptances of such polarity and magnitude as to cause the phase-frequency characteristic of the delay line to become linear in nature.

15

8. Apparatus for combining and for separating a plurality of signals whose frequencies are distributed within a given range of frequencies, comprising in combination:

an array of commutating hybrids, each hybrid comprising first and second waveguide means for defining a pair of ports at one end of the hybrid and a further pair of ports at the other end of the hybrid in which one of said ports defines a load termination, a first 3dB coupler connected between said first and second waveguide means at said one end

25

30

35

of the hybrid and a second 3dB coupler connected between said first and second waveguide means at said other end of the hybrid to define a predetermined waveguide length between said couplers within said first waveguide means, said second waveguide means defining a delay line between said couplers having a length greater than said predetermined length;

said second waveguide means comprising separate waveguide sections and a further 3dB coupler connecting such sections to provide a pair of waveguide stubs, and means terminating said waveguide stubs in short circuits whereby to provide susceptance loading of said stubs, at least one of said stubs having a mismatch along its length to provide susceptance loading which establishes a desired phase-frequency characteristic of the distribution of said frequencies within said range.

9. Apparatus as defined in claim 8 wherein said mismatch is effected by separating said one stub into two sections, one of which is displaced relatively to the other in the direction of the H-plane.

10. Apparatus as defined in claim 8 including a second mismatch along the length of the other waveguide stub, one mismatch establishing positive susceptance loading and the second mismatch establishing negative susceptance loading, the two loadings being related so as to provide a linear phase-frequency characteristic for said frequencies.

11. Apparatus as defined in claim 10 wherein said stubs are parallel and said mismatches are effected by separating said stubs into two sections which are displaced relatively to each other in the direction of the H-plane.
